DESCRIPTION

FIG. 1 is a perspective view of a water meter housing showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is another perspective view thereof shown in an exploded view; and,

FIG. 9 is a cross-sectional view taken along line 9—9 of FIG. 6.

The broken lines shown herein are for illustrative purposes only and form no part of the claimed design.
